UNITED STATES PATENT OFFICE.

SAMUEL C. LEWIS, OF CINCINNATI, OHIO, ASSIGNOR TO THE CINCINNATI COFFIN COMPANY, OF SAME PLACE.

DESIGN FOR A COFFIN ORNAMENT.

SPECIFICATION forming part of Design No. 15,601, dated December 9, 1884.

Application filed October 2, 1884. Term of patent 7 years.

To all whom it may concern:

Be it known that I, SAMUEL C. LEWIS, a citizen of the United States, residing at Cincinnati, in the county of Hamilton and State of Ohio, have invented a certain new and original Design for a Coffin Ornament, of which the following is a specification, reference being had therein to the accompanying drawing.

10 The nature of my design is clearly shown in the annexed photographic illustration, wherein a stranded anchor appears in relief above a background that is suggestive of the bed of the ocean. This background includes sea-weeds, 15 grasses, rocks, &c., and one of the anchor-flukes is shown as having caught hold of one of said rocks. It is evident, however, that this exact arrangement of objects need not be rigidly followed in every case, as my invention is de-

signed to cover an anchor having a background that represents or suggests the ocean-bed strewn with weeds, grasses, and rocks of any kind, and disposed around the anchor in any appropriate manner.

I claim as my invention—

25 The design for a coffin ornament, substantially as herein shown and described, which design consists of a stranded anchor having a background representing the bed of the ocean, the latter being strewn with sea-weeds, grasses, 30 and rocks.

In testimony whereof I affix my signature in presence of two witnesses.

SAMUEL C. LEWIS.

Witnesses:

JAMES H. LAYMAN,
SAM'L S. CARPENTER.
